WASHING MITT

Robert Servin, Jenkintown, Pa., assignor to Robert Hosiery Mills, Inc., Trappe, Pa., a corporation of Pennsylvania

Filed Apr. 11, 1962, Ser. No. 69,672

Term of patent 14 years

(Cl. D9—2)

FIG. 1

I claim:

The ornamental design for a washing mitt, substantially as shown.
